INVENTOR.

Frank L. Lloyd
BY

Mann & Co.
ATTORNEY'S.

UNITED STATES PATENT OFFICE

FRANK L. LLOYD, OF BALTIMORE, MARYLAND, ASSIGNOR TO THE CROWN CORK AND SEAL COMPANY OF BALTIMORE CITY, OF BALTIMORE, MARYLAND, A CORPORATION OF MARYLAND.

CROWNING MACHINE.

Application filed May 15, 1920. Serial No. 381,593.

To all whom it may concern:

Be it known that FRANK L. LLOYD, a citizen of the United States, residing at Baltimore, in the State of Maryland, has 5 invented certain new and useful Improvements in Crowning Machines, of which the following is a specification.

This invention relates to an improved machine for applying crowns or seals to bottles and has particular reference to a machine that is to be manually operated and which is of a portable character in that it may readily be clamped to a table or other support and as readily removed when desired.

One object of the invention is to provide a machine of such construction as to enable it to be built for a few dollars; which will seat and lock the crowns in sealing engagement 20 with a bottle-neck and which may be operated by unskilled persons.

The invention is illustrated in the accompanying drawings, wherein,—

Fig. 1. shows the improved machine in front elevation with a portion of one of the guide devices broken away for illustrative purposes.

Fig. 2. illustrates the same in substantially central vertical section.

Fig. 3. shows a vertical sectional detail through the bottle-support but viewed from the side opposite to that shown in Fig. 2.

Fig. 4. illustrates the bottle-support in plan view and the two side guide devices in 35 horizontal cross-section.

Fig. 5. shows a vertical cross-sectional detail through the adjustable horizontal crown-seating bar and crimping head.

Fig. 6. illustrates in rear elevation the link 40 connection between the bottle-support and the movable rod-carrying bar.

Fig. 7. shows one end of the crowning bar in top or plan view, and

Fig. 8. illustrates in perspective the pivot- 45 end of the operating lever.

In the drawing the numeral 9, designates the bottle-support having a flat top surface on which the bottom of a bottle 10, may be seated during the sealing operation. This

bottle-support is provided with a downwardly-projecting arm 11, having reinforcing ribs 12, and a lateral extension 13, so that a clamp 14, operated by a screw 15, which is threaded through the lateral extension may actuate the clamp which has 55 position beneath the bottom side of the bottle-support.

At each side, the bottle-support carries a vertically-extending tubular guide device 16, each of which has a vertical passage 17, 60 extending therethrough with contracted bearing openings or ends 18, at the upper and lower ends of said passage, as clearly shown at the left hand of Fig. 1.

To provide reinforcement for the bottle-support the under side of the latter has a vertically-depending rib 19, which extends from the lower ends of the guide devices across the under side of the support.

Two spaced-apart trunnion-lugs 20, extend rearwardly from the rib 19, and entrance to these lugs is gained from their rear for a purpose that will presently be explained.

Beneath the bottle-support there is provided a cross-bar 21, having a vertical rib 22, extending longitudinally across the upper side thereof and also provided at each end with an internally threaded socket 23. Each socket 23, receives the lower threaded 75 end of a vertical rod 24, and the positions of these rods are such that they will register with and extend vertically through the tubular guide devices 16, at opposite sides of the bottle-support.

The vertical rods 24, have a sliding fit in the bearings openings 18, so they may be vertically reciprocated through the guides 16 when the cross-bar 21, is raised or lowered through means that will presently be explained.

The vertical rods 24, sustain a horizontal crowning bar 25, which latter is provided with a crimping head 26, that depends from the under side of the bar and which has 95 crowning cavity 27, in its under side, as best illustrated in Figs. 2 and 5 of the drawing.

The crowning-bar 25, is provided with

vertical openings 28, at each end thereof through which the rods 24, extend, and these openings are somewhat elongated in a direction longitudinally of the bar, as shown in Figs. 5 and 7, of the drawing, so that said bar may have a slight horizontal movement with respect to the vertical rods 24, also for a purpose presently to be explained.

By reference to Figs. 2 and 5 of the drawings, it will be noted that between the two sets of vertical end-openings 28, the crowning bar has a horizontal passage 29, and that a horizontal rod 30, is located in said passage and is of a greater length than the distance between the inner ends of the two sets of end openings so that at least one end of this rod 30, may extend in a vertical plane beyond the inner ends of at least one set of the openings 28.

20 The rod 30 is so disposed in the horizontal passage 29, that its two vertical ends 31, will have position close to the circumferential surfaces of the two vertical rods 24, which pass through the crowning bar.

25 An adjusting screw 32, passes through a threaded passage 33, in one end of the crowning-bar 25, and the inner end of this screw contacts with vertical surface of the guide rod 24, at that end.

30 From the above explanation in connection with Fig. 5, of the drawing it seems to be obvious that when the screw 32, is turned to move forward that its inner end will engage one side of the one rod 24, and spring the latter slightly in the elongated openings 28, so that the diametrically-opposite side of said rod 24, will be crowded against one end of the horizontal rod 30, and thereby push the latter rod horizontally until its opposite end, 40 by engaging the other vertical rod 24, will bind the latter against the extreme far ends of the other set of elongated openings 28, in the opposite end of the crowning-bar. By this means a rigid clamping of the crowning-bar and the two vertical rods 24, is effected and as successfully accomplished as would be effected by the use of two clamping screws 32,—one for each vertical rod, and moreover the operation of one screw effects a clamping 45 action on both vertical rods.

50 In the manner just described the crowning-bar may be vertically adjusted on the two rods 24, and at any position above the bottle-support to make it effective to crown bottles of various heights.

To effect the crowning of a bottle it is necessary that the lower bar 21, the two vertical rods 24, and the crowning-bar 25, all be moved downwardly so that the crowning head 26, may seat and crimp a crown 34, on a bottle mouth.

This vertical movement of the crowning devices is effected by means which will now be explained.

The cross-bar 21, is provided on its forward side with two spaced-apart lugs 35 and 36 respectively,—the lug 35 being provided at one side with a horizontal recess 37 which is indicated by broken lines in Fig. 6, and in vertical section in Fig. 2, of the drawing.

55 An actuating lever 38, has a hand-engaging end 39 and a fulcrum-end 40, which latter end is provided with pivot-lugs 41 that project at opposite sides of said lever, as best illustrated in Fig. 8 of the drawing, and between the hand-engaging end and the pivot-lugs, said lever is provided with a cross-wise perforation 42.

80 The lever projects beneath the bottle-support 9, and the pivot-lugs 41, seat in suitable bearing sockets 43, that are formed in the lugs 20, on the bottom of the bottle-support so that the lever may be rocked on the pivot-lugs at its forward end.

85 A link-bar 44, has a laterally-projecting pivot-lug 45, at its upper end which enters the perforation 42, in the lever 38, and at its lower end said link-bar is provided with a trunnion-lug 46. The trunnion-lug 46, of this link-bar projects into the horizontal recess 37, of lug 35, and is pivotally retained therein.

90 A spiral spring 47, has its upper end secured at the under side of the bottle-support and its lower end attached to the lower cross-bar 21, and said spring holds the cross-bar in its normally elevated position under the bottle support as shown in Fig. 2 of the drawing.

95 As the cross-bar 21, is connected by the link-bar 44, to the lever 38, and the latter is pivoted in front of the link-bar connection, it follows that when said cross-bar is elevated the free end 39 of the lever will also be elevated. The spring 47, therefore keeps these parts in the normally elevated position shown in Fig. 2.

100 In as much as the vertical rods 24, and the crowning bar 25, are sustained from the lower cross-bar 21, they too will be held in their upward positions as shown in Figs. 1 and 2 when the lower bar 21, is held up by the spring 47.

105 A cotter-pin 48, extends through the reinforcing ribs 12 and crosses in front of the pivot-end of the lever 38, so as to retain the lugs 41, in the bearing sockets 43, and prevent accidental displacement.

110 In operation, a bottle 10, is seated upon the support 9, which latter is rigidly clamped by the screw-clamp 14—15, to a table or other device. Normally the lower bar 21, the two rods 24 and the crowning-bar 25, are all held elevated by the upward pull of the spring 47. The bottle is placed on the support with the mouth directly beneath the crimping head 26, and a metal crown or sealing cap 34, is placed loosely by hand on the

bottle mouth, all as shown in Fig. 1 of the drawing.

The operator may then grasp the handle-end 39, of lever 38, and depress the same,— 5 the lever taking the position shown in Fig. 3. During the depressing operation the pivot-lugs 41, on the inner end of the lever and the bearing sockets 43, in the lugs 20, serve as trunnion bearings for the lever-end to 10 rock upon, and as the lever is moved downwardly the link-bar 44, pushes the lower cross-bar 21, downwardly against the action of the spring 47, which latter will stretch during this movement. As bar 21, moves 15 down it draws down the two rods 24, which latter travel through and are guided by the two stationary guide-tubes 16, on the bottle-support, and this downward movement of the rods causes a like movement of the upper 20 horizontal crowning-bar 25, and head 26, on the under side of the latter.

As the crowning-bar 25, nears the loose crown or sealing cap 34, on the bottle-mouth the operator may, with the hand not engaged 25 on the lever, slightly alter the position of the bottle to bring the cavity 27, of the head and the crown into register, so that the top of the crown may enter the cavity of the head.

30 A further downward movement of the bar 25, and head 26, will first seat the crown on the bottle mouth and slightly greater movement will cause the annular rim 49 of the head to engage the corrugated flange on the 35 crown and crimp it into locking engagement with the shoulder usually provided on the bottle-neck for that purpose.

Upon releasing the lever the spring 47, will return the parts to the normal position so the 40 sealed bottle can be removed and another bottle substituted, whereupon the operation may be repeated.

Having described my invention, I claim,—

1. The combination with a bottle support 45 having tubular guides extending vertically therefrom and rigid therewith, of a cross-bar beneath the support, a rod at each end of the cross-bar and extending up through the tubular guides of the support, a hand 50 lever pivotally sustained above the cross-bar and having a connection with the latter and a crowner head carried by the rods above the said support.

2. The combination with a bottle support 55 having rigid tubular guides extending vertically therefrom, of means for securing the support and its guides to an object, a horizontal cross-bar immediately beneath the support, a rod at each end of said cross-bar 60 said rods extending vertically through the rigid guides on the support, a hand lever pivoted to the under side of the support above said cross-bar, a connection extending downwardly from the hand lever to said

cross-bar and a crowner-head carried by the rods above the support.

3. The combination with a bottle support having rigid tubular guides extending vertically therefrom, a cross-bar beneath said support and guides, a rod at each end of said cross-bar said rods extending vertically through the rigid guides, a lever pivoted to the under side of the support above said cross-bar and having a connection extending down to and engaging the said cross-bar, a 70 crowner head carried by the rods above the tubular guides and means for adjustably clamping said crowner head to said bars.

4. The combination with a bottle support having a rigid tubular guide at each of two 80 opposite sides thereof and also having a clamp device to attach it to an object, of a cross-bar beneath said support, a rod at each end of the cross-bar and said rods extending vertically through the rigid guides, 85 a crowner head carried by the rods above the rigid guides and support, means on the interior of the crowner head and extending between the two rods for adjustably holding the crowner head on the rods and means for 90 moving the rods vertically to operate the crowner head.

5. The combination with a bottle support, of two rods extending above the support, a 95 crowner-bar extending horizontally between and sustained by the rods above the support, means sustained by the crowner-bar and also extending between the rods to engage the latter, means for clamping the rods, the 100 crowner-bar and the means sustained by the latter to lock the crowner-bar against movement on the rods and means for effecting a relative movement between the rods and the crowner-bar with respect to the support.

6. The combination with a bottle support, 105 of two rods extending above the support, a crowner-bar above the support and having elongated passages through which the rods extend, means carried by the crowner-bar for clamping the bars against the end walls 110 of said elongated passages to adjustably lock the crowner-bar and rods together, and means for effecting a relative movement between the rods and the support.

7. The combination with a bottle support, 115 of two vertical rods extending above the support, a crowner-bar above the support and having two elongated passages through which the rods extend, a horizontal rod carried by the crowner-bar and located between 120 the two vertical rods, means also carried by the crowner-bar for clamping the vertical rods, the crowner-bar and the horizontal rod together to lock the crowner-bar on the vertical rods, and means for effecting a relative movement between the vertical rods and support.

8. The combination with a bottle support

having tubular guides extending vertically therefrom and rigid therewith and said support also having a clamp device for securing it to an object, of a hand lever having one end pivotally sustained at the under side of the support, a cross-bar below the pivoted end of said lever, a connection between said

lever and the cross-bar beneath it, rods having their lower ends attached to the cross-bar and extending up through the guides of 10 the bottle support and a crowner-bar carried by said rods above the support.

In testimony whereof I affix my signature.

FRANK L. LLOYD.
